UNITED STATES PATENT OFFICE.

CHARLES A. JUENGST, OF CROTON FALLS, NEW YORK.

STAPLING-MACHINE.

No. 813,215.

Specification of Letters Patent.

Patented Feb. 20, 1906.

Application filed April 29, 1904. Serial No. 205,448.

To all whom it may concern:

Be it known that I, CHARLES A. JUENGST, a citizen of the United States, residing at Croton Falls, in the county of Westchester 5 and State of New York, have invented an Improvement in Stapling-Machines, of which the following is a specification.

My invention relates to a machine for automatically binding or, in other words, connecting together sheets or signatures by wire staples to form pamphlets or small books, with the object of compactly arranging the parts and also so arranging, constructing, and grouping the parts that the device is fully and 15 equally operative when the parts are placed vertically with the signatures or sheets horizontal or when the parts are placed horizontal with the signatures or sheets vertical.

My improved machine comprises a platform 20 supporting the group or groups of signatures or sheets to be stapled and preferably a conveyer for progressively moving the same along. Standards secured to and rising from this platform support a bar carrying the reels 25 of wire for the staples and also serve as guides for a vertically-movable feed-bar for moving the wire forward and for a presser-bar adapted to bear upon the group of signatures or sheets at the time the staples are applied. 30 This presser-bar carries swinging yielding die-blocks positively held for the moment that the wire is cut and one end is overturned to form the staples, and which die-blocks when released are moved down and swing with the 35 downward movement of the parts to force the staples through the group of signatures or sheets. The cutters and said holding devices are actuated by rocker-arms and face-cams on a revoluble power-shaft. A crank 40 on this shaft and connecting-rod and a cross-bar connected thereto effect the vertical movement of rods which in turn cause or permit the movement of the feed-bar and presser-bar and also a cross-head and plungers attached thereto, all of which are herein-after more particularly described.

The conveyer hereinbefore referred to is the conveyer of a signature and sheet gathering machine, from which the piles of signatures or sheets are progressively delivered to the stapling-machine to be bound as collated.

In the drawings, Figure 1 is an elevation and partial section representing my improved machine. Fig. 2 is a side elevation and section on the dotted line x x of Fig. 1,

and Fig. 3 is a sectional plan at the line y y of Fig. 1.

The platform a is suitably supported. It is provided with a rib a' at a slight distance from the edge at the left hand of Fig. 2. The platform is also provided with guide-sleeves a², extending downward from the under side of the platform. There are in the platform openings 2, in which dogs 3 are pivoted, and the platform is provided with a chain-conveyer device 4, having posts 5 at intervals and extending from a signature and sheet gathering machine, and b represents a pile of signatures or sheets upon the platform a and against one edge of which the post 5 rests, the 70 conveyer and post, as shown in Figs. 2 and 3, being in the act of moving the pile of signatures or sheets along upon the platform. It will be noticed that the rib a' along one edge forms a guide for the pile of signatures or sheets and 75 also a means of keeping them true in relation to one another.

c d are standards having flanged lower ends that rest upon the platform and threaded portions passing through the platform and 80 nuts 6 on the lower ends to secure the standards in place. These standards are provided with pins 7 and collars 8 and below the collars 8 there are springs c' d'. The upper ends of the standards c d are exteriorly 85 threaded, and a bar e extends across between and is connected to and supported by the standards c d, the same being secured in place to the standards by the nuts 10. The bar e has upward extensions or bracket-arms e', 90 with pins 11, which form the axes for the reels e² of wire, from which the staples are made.

Upon the back of the bar e there are series 95 of guiding and straightening rollers f f', between which the wire as it comes off the reel passes, and below these groups of guide and straightening rollers are pairs of dogs 12 13, which bear at one side upon the wire, there being lugs on the bar e (shown in Fig. 1 by 100 dotted lines) at the other side of the wire. The dogs are preferably spring-actuated, so as to be kept up against the wire, and they serve the purpose of holding the wire in position to prevent any upward movement of the 105 wire with an upward movement of other parts of the machine.

A feed-bar g extends across the machine. It is perforated for and slides upon the standards c d. This feed-bar is also provided with 110

lugs on the back and with spring-actuated groups of dogs 14 15, the wire from the reels passing through between the lugs and the dogs. The upward position of the feed-bar 5 g is determined and limited by the nuts 9 upon the standards $c d$, which nuts may be moved along the threaded parts of the standards to effect the desired adjustability.

h is a presser-bar with extensions h' at its 10 ends, which are perforated for the standards $c d$, the springs $c' d'$ coming between the upper surfaces of these extensions h' and the under surfaces of the collars 8. This presser-bar is of appreciable area and weight. It is 15 notched longitudinally, as will be seen in Fig. 2, to straddle the rib a' of the platform, so that its vertical movement is not interfered with by the rib. The presser-bar h is transversely slotted and provided with lugs 16 in 20 pairs, to and between which are pivoted the die-blocks $i i'$. The shape of these die-blocks will be apparent, especially from Fig. 2. The under surface is semicircular, and the surface thereof in position agrees substantially with 25 the base of the presser-bar h . The back end of each die-block is heavier than the forward end, which is tapering in the form of a hook, and the upper edge of the forward part is flat. The presser-bar h is perforated or apertured 30 from opposite ends, the upper aperture at each end receiving the cutter-bars k and the lower apertures at the respective ends the locking-bars l . The portion, Fig. 1, in section shows the relation of the locking-bar l 35 and the cutter-bar k to the presser-bar h and the die-block i in the extreme movement in one direction. Each locking-bar passes through a hole in its coacting die-block a little in advance of the end of the cutter-bar, so 40 that the die-block is held in position. Each cutter-bar k at its outer end is turned at a right angle and provided with a pin k' , and the upper ends of the locking-bars are bent up at a right angle and pass through openings 45 in the cutter-bars to connect the cutter-bars and locking-bars together.

I provide rocker-arms $m m'$, pivoted at 17 to the platform a , which at their lower ends are provided with rollers and at their upper 50 ends are forked to receive the pin ends k' of the cutter-bars. I have shown and may prefer to employ springs 18 between the guide-sleeves a^2 and the rocker-arms $m m'$ for effecting the return movement of the rocker-arms. 55 The power-shaft n is supported in brackets b' to and from the under side of the platform a . On this power-shaft are cams n' , acting upon the rollers of the rocker-arms $m m'$ to swing 60 the rocker-arms in one direction, the direction of such movement being toward the opposite ends of the presser-bar h , the springs 18 or equivalent devices returning the rocker-arms to their initial position. Upon this power-shaft n is a crank-arm n^2 and a 65 cam n^3 , which in part performs the office of

the other crank-arm, there being a crank-pin between the crank-arm and the cam to which the connecting-rod 19 is fastened. The cross-bar 20 is provided with heads 21 at its ends, and to this cross-bar the opposite end of the 70 rod 19 is connected. The rotation of the power-shaft n , the crank-arm n^2 , and cam n^3 with the movement of the rod 19 serves to raise and lower the cross-bar 20 and its heads 21. I provide vertical rods $o o'$ at their lower 75 ends secured in the heads 21. These rods pass through the guide-sleeves a^2 of the platform. They pass on up through the opposite ends of the presser-bar h through openings in the feed-bar g and the bar e , the openings in the bar e being guides for the upper ends of these rods. Upon these rods $o o'$ are 80 collars 27, pinned thereto between the feed-bar g and the bar e . The rods $o o'$ also pass through the cross-head r , which is pinned 85 thereto, and between the cross-head r and the feed-bar g , around the rods $o o'$, are springs 26. The cross-head r carries the plungers r' , which are secured thereto and which pass down through vertical apertures 90 in the presser-bar h , which apertures intersect the openings for the cutter-bars k and locking-bars l and are directly in line with the positions of the die-blocks $i i'$. Pins 24 pass through the rods $o o'$ and through slots 95 25 in the opposite ends of the presser-bar h from the lower edges of said bar up to said pins. I further provide a T-head 23 with a rounded lower end adapted to rest upon the upper surface of the cam n^3 , and which T-head is held in position and guided by a pin 22, depending from the under surface of the platform a . The wires to form the staples from the reels e^2 pass down between the series of guiding and straightening rollers $f f'$, 100 between the lugs of the bar e and the pairs of dogs 12 13, between the lugs of the feed-bar g and the series of dogs 14 15, back of the cross-head r , and through openings provided therefor in the presser-bar h immediately along- 105 side of the openings provided for the plungers r' .

The operation of the device is substantially as follows: The parts shown in Fig. 1 are in the relation which they will assume 115 when a pile of signatures or sheets has been brought along by the conveyer device 4 to a predetermined position on the platform and the cams n' have moved the rocker-arms $m m'$, forcing the locking-bars l and cutter-bars k 120 into the presser-bar h to first lock the die-blocks $i i'$ in position and then to cut off the wire and bend the upper ends of the wire, which agree with the vertical thickness of the cutter-bars, over upon the upper surfaces 125 of the die-blocks $i i'$, so as to form the first bend of the staples. In this position it will be noticed that the crank-pin of the crank-arm n^2 and cam n^3 is at its highest point. (See especially Fig. 2.) As the same moves down 130

the cross-bar 20, the rods $o\ o'$ and the pins 24 move downward. The quick-acting cams $n\ n'$ change position, so that the springs 18 or equivalent devices act upon the rocker-arms $m\ m'$ to withdraw the cutter-bars k and locking-bars l from their active position and release the die-blocks $i\ i'$. As this movement takes place the presser-bar h lowers both by gravity and by the expansive action 5 of the springs $c\ d'$, the cross-head r and plunger r' follow down with the presser-bar, and the collars 27 move down to contact with the upper surface of the feed-bar g . At this moment the presser-bar is in forcible contact 10 with the pile of sheets or signatures to hold the same in position. The further downward movement of the rods $o\ o'$ by the action of the connecting-rod 19 and the cam device brings the lower ends of the plungers r' into 15 contact with the bent end of the staple upon the upper surface of the forward portions of the die-block and moves the feed-bar g in proportion because of the collars 27 resting thereon. This downward movement advances 20 the wire for the next staples, because the function of the dogs 14 15 is to so hold the wire that the feed of the same is bound to take place. This downward movement continues 25 the pressure exerted by the plungers r' upon the staples and the upper surfaces of the die-blocks, gradually swinging the die-blocks upon their pivotal connection with the lugs 16; the same moving out of the way as the parts and the staples move down. The 30 fact that the presser-bar bears with force upon the signatures or sheets compels the end of the wires forming the staples in their grooves to be pushed through the signatures or sheets with the progressive movement of 35 the parts until the bent ends of the wires rest upon the upper surface of the pile of signatures or sheets, the downward movement at this time having been entirely completed, with the lower ends of the wires forming the 40 staples projecting from the under surface of the signatures or sheets. With the upward movement of the bars $o\ o'$, returning the parts to their initial position, the various series or 45 groups of dogs slip past the wire to engage a new portion, the plungers rise out of the way, to the cams n' act upon the rocker-arms $m\ m'$ to force the locking-bars l and cutter-bars k toward the position shown in Fig. 1, in which the die-blocks are held and the wire cut off for 50 the next staples, and the ends turned over upon the upper surfaces of the die-blocks. Simultaneous with this movement the cam n^3 in its rotation and, in fact, substantially coincident with the extreme downward 55 movement of the parts, the pointed end of the cam acts upon the under side of the T -head 23 to raise the same toward and against the under surface of the platform a , swinging the dogs 3, pivoted in the openings 2, upward. These dogs are so placed that the pro-

jecting wires of the staples are right in line with the dogs and, in fact, are slightly bent by the dogs as they pass through the pile of signatures or sheets, and this upward movement with force bends the lower portions of 70 the wires against the under surfaces of the signatures or sheets to complete the form of the staple and to hold the signatures or sheets between the opposite bent ends thereof. These operations are thereafter progressively 75 repeated with new piles of signatures or sheets. The special office performed by the nuts 9 in their adjustable character is to permit the feed-bar g to move farther along the rods $o\ o'$, so that the groups of dogs 14 15 80 connected thereto can engage the wires farther along in their length, so that with each movement a greater length of wire is taken up for a longer staple in proportion to the thickness of the pile of superimposed signatures or sheets going to make up the small book or pamphlet. The springs 26 between the cross-head r and feed-bar g keep these parts separated and are sufficient to raise the bar g to contact with the nuts 9 wherever 85 they may be placed. They, however, will yield for the extreme movement of the several parts with relation to one another, so that the full movement of the cam device through the rods $o\ o'$ may be imparted to the 90 feed-bar g and the wires for the lengths of the staples desired.

I claim as my invention—

1. In a stapling-machine, the combination with a platform upon which the signatures or sheets to be connected rest, of means for progressively feeding the wire, a presser-bar adapted to come down on the signatures or sheets to hold the same in position, means for cutting the wire to form a staple and for 100 simultaneously bending one end thereof, means for forcing the staple-wire through the signatures or sheets, and means for bending the wire on the under side of the signatures or sheets to complete the staple and hold the 105 signatures or sheets together.

2. In a stapling-machine, the combination with a platform upon which the signatures or sheets to be connected rest, of means for progressively feeding the wire, a presser-bar 110 adapted to come down on the signatures or sheets to hold the same in position, die-blocks and means for pivoting the same to the presser-bar, means for cutting the wire against the die-blocks to form a staple, and 115 for simultaneously bending one end thereof; means for holding the die-blocks while the wire is cut, means for forcing the staple-wire through the signatures or sheets, and means for bending the wire on the under side of the 120 signatures or sheets to complete the staple and hold the signatures or sheets together.

3. In a stapling-machine, the combination with a platform upon which the signatures or sheets to be connected rest, and means for 125

sheets, a power-shaft, cams on the power-shaft, rock-shafts actuated by the cams for simultaneously moving the pairs of cutter-bars and locking-bars, the locking-bars momentarily holding the die-blocks in position while the cutter-bars cut the wire and bend similar ends of the same over the upper surfaces of the die-blocks, a crank device on the rock-shaft, devices connected to the crank 5 device for effecting the movement of the wire-feed devices and the cross-head and plungers

and permitting the presser-bar to come down upon the signatures or sheets, and a device actuated by the cam device for moving the aforesaid dogs to complete the bend of 15 the staples.

Signed by me this 22d day of April, 1904.

CHAS. A. JUENGST.
